A. R. ROSS

ELECTRIC BAKE OVEN

Filed Sept. 10, 1924

INVENTOR
ALLEN R. ROSS

BY

Richard J. Cook
ATTORNEY

UNITED STATES PATENT OFFICE.

ALLEN R. ROSS, OF SEATTLE, WASHINGTON.

ELECTRIC BAKE OVEN.

Application filed September 10, 1924. Serial No. 736,955.

To all whom it may concern:

Be it known that I, ALLEN R. ROSS, a citizen of the United States, and a resident of Seattle, King County, Washington, have invented certain new and useful Improvements in Electric Bake Ovens, of which the following is a specification.

This invention relates to improvements in electrically heated ovens and more particularly to ovens of the larger types such as are adapted for use in restaurants, bakeries, hotels and like places, the invention relating particularly to a construction that provides for the removal, or replacing of heating elements while the oven is in use.

In order to give a clearer understanding of the objects of the invention, it will be stated here that ovens of this type have heretofore been so constructed that the heating elements have to be inserted or removed through the oven door. An objection to this method of construction is that should an element burn out or become damaged while the oven is in use, it is necessary that the oven door be held open for such an extended period that the oven becomes cooled off and there will be a resultant damage to the material being baked.

It will further be stated here that with ovens that require that the heating elements be removed, or inserted, through the oven door, difficulty is experienced and more time is required for the replacing or installing of elements than by the improved construction hereinafter described.

In view of the above mentioned objections, it has been the object of this invention to provide an oven of such construction that should it be necessary, or desirable, to do so the elements may be removed, or replaced, without necessitating the opening of the oven door or the removal of any wall or other part that would permit the escape of heat, or the inflow of cooler outside air into the oven.

Other objects of the invention reside in the various details of construction and combination of parts as will hereinafter be described.

In accomplishing these and other objects of the invention, I have provided the improved details of construction, the preferred forms of which are illustrated in the accompanying drawings, wherein—

Figure 1 is a front, perspective view of a part of an oven embodying features of con-

struction, in accordance with the present invention.

Figure 2 is an enlarged, vertical sectional view of the oven showing the construction embodied by this invention.

Figure 3 is a horizontal section taken on the line 3—3 in Figure 2.

Referring more in detail to the several views of the drawings—

In its preferred form of construction, the outer walls of the oven would be made up of spaced apart sheet metal plates 1 and 2, between which an insulating material 3, such as asbestos fibre or other suitable material, is packed. The oven could be made to contain a plurality of compartments 4 wherein the baking is done and each of these, as shown in Figure 2, extended to the front of the oven where a door frame 5 is fitted therein.

As shown best in Figures 2 and 3, the door frame 5 is of rectangular form, of sheet metal construction, and extends substantially within and also forwardly of the opening. It is of such width that its opposite end portions fit against the opposite sides of the oven and are secured rigidly thereto by means of the angle iron members 6 which have their flanges bolted, or otherwise fixed, respectively to the sides of the frame and to the front oven wall as shown in Figure 3.

The upper and lower walls of the frame 5 are spaced from the adjacent walls of the oven to provide spaces, through which the electric elements 7, whereby the oven is heated, may be inserted or removed. These elements are mounted on a frame comprising transverse bars 8 which, at their opposite ends, are supported upon angle iron strips 9 secured to the side walls of the oven. These elements may be removed bodily from the oven through the spaces between the door frame and the upper and lower walls of the compartment 4. In Figure 1, I have shown the lower space below the door frame enclosed.

Normally the spaces below and above the door frame are closed by removable, packed inserts, each of which consists of a channelled member 10 that is fitted within the space to be closed thereby and which has its outer flange 10^a extended to overlap the front wall of the oven to which it is secured by screw bolts or the like, 12. The inner flange 10^b of the channel is turned laterally along its up-

per edge toward the outer flange, and between these two flanges and the base of the channel is an insulating packing 14. Angle iron strips 15 are detachably secured by bolts 16 extended through their flanges to the top and bottom wall portions of the door frame and to the outer flanges 10^a and of the channel members. These latter strips serve as an additional support for the door frame to add rigidity to the structure and insure a tighter construction.

An insulated door 20 of a suitable type is pivotally mounted in the frame 5 to swing inwardly from its upper edge and its closing movement is limited by engagement with inwardly inclined cleats 21 secured to the end walls of the frame.

Assuming that the oven is so constructed and that it should be necessary to replace or remove one of the elements 7 during a baking operation, it is only necessary to remove the bolts or screws 12 that hold the flange 10^a to the front wall of the oven and those that attach the angle 15 to the door frame and to then draw the channel iron insert outwardly. The element 7 may then be removed through the open space thus provided and replaced by a new one and the opening again closed by the insertion of the channel. This does not necessitate the opening of the oven door and requires but a few seconds time, thus avoiding the cooling off of the oven and the loss of the material being baked.

Having thus described my invention, what I claim as new therein and desire to secure by Letters-Patent, is:

1. An oven of the class described having a wall opening, a door frame located in the opening and providing spaces between the frame and edges of the opening through which heating elements for the oven may be removed or inserted and closure members removably fitted in said spaces.
2. An oven of the class described having a wall opening leading into the oven, a door frame fitted in the opening and providing

spaces between it and the upper and lower edges of the oven opening through which heating elements may be removed or inserted, closures removably fitted in said spaces and means whereby they may be detachably secured to the frame and to the oven wall.

3. An oven of the class described having a wall opening leading into the oven proper, a door frame disposed in said opening and providing spaces between its upper and lower walls and the edges of said opening through which heating elements for the oven may be removed or inserted, means secured to the end walls of the frame and to the oven walls whereby the frame is rigidly supported; closures for said spaces, above and below the frame, removably fitted therein and having flanges adapted to overlap the oven wall adjacent said opening and screws, or the like, extended through said flanges and into the oven wall whereby said closures may be held removably in place.

4. An oven of the class described having a wall opening leading into the oven, a rectangular door frame disposed in the said opening so as to provide spaces above and below it through which heating elements for the oven may be inserted or removed; said frame extending partly within and partly from the oven, angle iron members secured to the ends of the frame and to the oven walls to support the frame rigidly in the opening, closure members for said spaces above and below the frame, each comprising a channel member wherein insulating packing is contained and having its outer flange extended to overlap the oven wall at the edge of the opening, means for detachably securing said overlapping flanges to the oven wall, and angle members extended along the frame at upper and lower sides, and detachably secured to the frame and to the outer flanges of said closure members.

Signed at Seattle, King County, Washington, this 29th day of August, 1924.

ALLEN R. ROSS.
